US00D769258S

(12) **United States Design Patent** (10) **Patent No.:** **US D769,258 S**
Hall et al. (45) **Date of Patent:** **** Oct. 18, 2016**

(54) **DISPLAY SCREEN WITH GRAPHICAL USER INTERFACE**

(71) Applicant: **Microsoft Corporation**, Redmond, WA (US)

(72) Inventors: **Martin Hall**, Seattle, WA (US); **Kelly McArthur**, Redmond, WA (US); **Andrew M. Pickard**, Seattle, WA (US); **Raymond Alexander Malkiewicz**, Seattle, WA (US); **Michael A. LaJoie**, Seattle, WA (US); **Evan Amarante Soares**, Seattle, WA (US); **Kristie E. Smith**, Kirkland, WA (US); **Conroy Williamson**, Kirkland, WA (US); **Sergey Kislev**, Woodinville, WA (US)

(73) Assignee: **Microsoft Corporation**, Redmond, WA (US)

(**) Term: **15 Years**

(21) Appl. No.: **29/532,115**

(22) Filed: **Jul. 1, 2015**

(51) **LOC (10) Cl.** **14-04**

(52) **U.S. Cl.**

USPC **D14/485**

(74) Attorney, Agent, or Firm — Banner & Witcoff, Ltd.

(57) **CLAIM**

The ornamental design for a display screen with graphical user interface, as shown and described.

DESCRIPTION

FIG. 1 is a front view of a display screen with graphical user interface showing our new design; and, FIG. 2 is an enlarged view of the display screen with graphical user interface shown in FIG. 1.

The broken line showing of the display screen, text, and graphic features forms no part of the claimed design.

1 Claim, 2 Drawing Sheets
